UNITED STATES PATENT OFFICE.

OSWALD BURGER, OF BERLIN-CHARLOTTENBURG, GERMANY, ASSIGNOR TO WESTINGHOUSE ELECTRIC & MANUFACTURING COMPANY, OF NEW YORK, N. Y., A CORPORATION.

ELECTRIC CONDENSER.

Application filed February 10, 1925, Serial No. 8,276, and in Germany February 12, 1924.

My invention relates to improvements in electric condensers.

It is well known that the capacity of a condenser is the greater the thinner its dielectric layer. Attempts have therefore been made to keep this layer as thin as possible. These attempts soon reached their limit owing to the difficulties which arose in producing and finishing the dielectric materials. If the layer is very thin a defective place will naturally form a relatively considerable part of its thickness. Such a weakened place will not be able to sustain the total voltage of the condenser and a puncture will occur which destroys the dielectric layer and thereby the entire condenser. To avoid the danger just mentioned it has hitherto been necessary to make the dielectric layer thicker than was desirable for the capacity of the condenser.

According to my invention this disadvantage is avoided by arranging between the conducting layer and the dielectric layer of the condenser a protective layer of semi-conducting material. When the dielectric is in faultless condition the resistance which the protective layer offers to the discharge current is relatively low and consequently also the voltage loss caused by it. When, however, there is a defective place in the dielectric which reduces its resistance, the resistance of the protective layer becomes of considerably greater importance in comparison with the diminished resistance of the dielectric.

The improved condenser is illustrated in the accompanying drawing, the single figure of which is a sectional view through a portion of a condenser embodying my invention. The effect of the protective layer will be clear from the following description and explanation. In the illustration, *d* is the dielectric layer, *s* the protective layer according to my invention and *m* the metal foil or conductive layer. When the dielectric is in perfectly faultless condition only that resistance of the protective layer comes into play which it offers to a current traversing it at right angles to its surface. Since this resistance is not great, the voltage drop in the protective layer is small. We assume now that at *a* there is a defective place in the dielectric *d*. The current which flows from the point *a*₁ across this place *a* through the dielectric towards the point *a*₂

finds a resistance in the protective lever *s* which is in proportion to the thickness of the protective layer and the area of the defective place. The resistance is considerable, owing to the small extent of the defective zone. If the current were to flow into the defective place *a* from other places, such as *b*, *b*₁, it would be obliged to pass obliquely through the protective layer in order to reach the defective place *a*. The length of the path of the current and therefore also the resistance which it encounters would thus become greater. The current intensity at the weakened place does not therefore, become essentially greater than in other parts of the dielectric so that no temperature rise and no destruction of the dielectric need be feared. From this it follows that when the dielectric is undamaged the resistance of the protective layer and consequently the voltage losses are practically negligible. When, however, the dielectric has become damaged, the protective layer comes into full operation. It is therefore possible to make the dielectric thinner than has been permissible heretofore, whereby dielectric material is saved on the one hand while, on the other hand, the capacity of the condenser is increased without the danger of short-circuits.

The thickness of the protective layer depends upon the circumstances, and in particular upon its conductivity in comparison with that of the dielectric. In many cases it is advisable to choose for the protective layer, a material which is not too poor a conductor, and to make it of considerably greater thickness than the dielectric. The protective layer may be disposed at one side of the dielectric only, as shown in the illustration, or at both sides.

What I claim as my invention is:—

1. In an electric condenser, the combination of a dielectric layer, conducting layers at both sides of said dielectric layer and a layer of semi-conducting protective material between said dielectric and one of said conducting layers, said layer of protective material being of considerably greater thickness than said dielectric layer.
2. A condenser comprising two conducting sheets separated by a dielectric, at least one of said sheets comprising a layer of good conductivity capable of carrying currents in a direction parallel to its surface and a sec-

110

- ond layer of such material as to greatly oppose substantially all currents except those flowing into the dielectric at approximately right angles to the surface thereof.
5. 3. A composite plate for an electric discharge device comprising a layer of good conductivity capable of carrying currents in a direction parallel to its surface and a second layer on one or both of its sides, said 10 second layer being of such material as to greatly oppose the flow of discharge currents in a direction substantially parallel to its surface, while permitting a relatively easy passage of currents to or from said first-mentioned layer in a direction normal to its surface.

4. In an electric condenser, the combination of a dielectric layer, conducting layers at both sides of said dielectric layer and a layer of semi-conducting protective material 20 between said dielectric and at least one of said conducting layers, said semi-conducting protective layer being of such thickness, in proportion to its conductivity, as to greatly oppose the flow of discharge currents in a 25 direction substantially parallel to its surface, while permitting a relatively easy passage of currents to or from said dielectric in a direction normal to its surface.

In testimony whereof I affix my signature.

OSWALD BURGER.
